UNITED STATES PATENT OFFICE.

HENRY R. DAVIES, OF TOLEDO, OHIO, ASSIGNOR, BY MESNE ASSIGNMENTS, TO THE ELECTRIC AUTO-LITE COMPANY, OF TOLEDO, OHIO, A CORPORATION OF OHIO.

IGNITION SYSTEM.

Application filed August 8, 1917. Serial No. 185,085.

To all whom it may concern:

Be it known that I, HENRY R. DAVIES, a citizen of the United States, residing at Toledo, in the county of Lucas and State of Ohio, have invented certain new and useful Improvements in Ignition Systems, of which I declare the following to be a full, clear, and exact description.

This invention relates to ignition systems for automobiles and more particularly to the timing mechanism thereof.

It is desirable in internal combustion engines to provide means whereby the time at which the spark takes place may be varied, thereby permitting an advance of the spark with an increase of speed to obtain the maximum efficiency and conversely permitting a retarding of the spark at lower speeds where there is danger of premature explosion which may result in "knocking" and a loss of power if not a reverse rotation of the engine shaft.

The object of my invention is to provide automatic means for varying the time of sparking. A further object of my invention is to provide a timer in which the spark will always be fully retarded at starting, and will be automatically advanced proportionately to the increase in engine speed.

Further objects of this invention relate to economies of manufacture and details of construction as will hereinafter appear from the detailed description to follow. I accomplish the objects of my invention in certain instances by the devices and means described in the following specification, but it is evident that the same may be varied widely without departing from the scope of the invention, as pointed out in the appended claims. Structures constituting certain embodiments of my invention, any one of which may be the preferred, are illustrated in the accompanying drawings forming a part thereof, in which:

Figure I is a diagrammatic view illustrating the wiring of an ignition system embodying my invention, the automatic means for advancing the spark being illustrated diagrammatically.

Figure II is a top plan view of the timer with the cover removed.

Figure III is a detail, vertical, sectional view, taken substantially on the line III-III of Figure II.

Figure IV is a section, similar to that

shown in Figure III, showing the interrupter lever plate lifted to its uppermost position.

Figure V is a detail, sectional view, taken substantially on the line V-V of Figure IV.

Figure VI is a detail, perspective view of the block carried by the interrupter lever for contacting with the actuating cam.

Figure VII is a sectional view corresponding to Fig. III, and showing a modified form of my invention.

Figure VIII is a sectional view similar to Figure VII showing another modified form of my invention.

Figure IX is a vertical, sectional view, corresponding generally to Figure III, but showing a modified form of my invention.

Figure X is a detail, sectional view, taken substantially on the line X-X of Figure IX.

Figure XI is a fragmentary, detail, sectional view, taken substantially on the line XI-XI of Figure IX.

In the drawings, similar reference numerals refer to similar parts throughout the several views, and the sectional views are taken looking in the direction of the arrows at the ends of the section lines.

Considering the numbered parts of the drawing, I have illustrated in Figure I the wiring of an ignition system, in which my invention is embodied. A direct current generator G has the main brushes 11 and 12. The main circuit connection 13 is connected to the brush 11 through a series field winding 14, and a connecting wire 15. The other main circuit connection 18 is directly connected to the brush 12, and the lamp load 17 is connected to the circuit connections 13 and 18 in parallel in the well known manner, a switch 16 being provided, by means of which the lamp load circuit may be broken.

Brush 19 is in operative contact with the commutator of the generator armature and is connected by a wire 20 to the shunt field 21, the other terminal of said field being directly connected to the main brush 11 through the wire 15. Between the main brushes 11 and 12 and in parallel with the lamp circuit, a storage battery 27 is connected, said storage battery being connected to the brush 11 through the wires 15, 22 and 23, provided with the switches 25 and 26, the other terminal of said battery being con-

nected to the wire 18 by the wire 24, at the point 28. Across the storage battery and the switch 26, I connect the primary ignition circuit, which includes the connecting wire 29, the primary coil 30, connection 31, interrupter arm 32, operated by the rotating cam 33, interrupter contacts 34, and wire 35. The condenser 37 is connected with the wire 31 and the wire 35 by means of the wires 36 10 and 38. The secondary circuit includes the ground 39, the secondary coil 40, wire 41, distributor arm 42, and the spark plug terminals 43, which are connected with the spark plugs, and through the spark plugs to 15 the ground, in the usual manner.

Within the casing which houses the interrupter and the distributor mechanism, and which is designated generally by the numeral 44, I provide means for varying the 20 sparking time, said means being diagrammatically illustrated in Figure I and comprising lever 45, which is adapted, when moved, to vary the time of sparking, one end of said lever arm being connected to a 25 core 47, which is disposed within a solenoid 48. The solenoid 48 is electrically connected with the brushes 19 and 12, through the wires 49 and 49'. The spark varying means is restored to its normal position by means 30 of the spring 46. It will be understood that this drawing is merely diagrammatic and is intended to indicate any means by which the variation in current strength in the circuit, formed by the wires 49 and 49' and solenoid 35 48, between the brushes 19 and 12, will act to vary the time at which the spark occurs, which means I refer to generally as spark advancing mechanism.

Figures II to V, inclusive, illustrate one 40 form which my invention may take. The casing 44 for the timer is made up of the cup-shaped casings, 50 and 51, which are disposed end to end, as shown in Figures III and IV, a ring 52 being provided, 45 which rests on the upper edge of the casing 51 and carries the cover 53 detachably secured to the top of the casing 51. Cover 53 carries the central contact for the distributor arm 42 and the spark plug terminals 43. The lower cup-shaped casing 50 is provided with a central boss 54, having a central opening therein, in which the rotating 50 shaft 55 is journaled. The upper casing 51 is disposed so that the edge of its base rests upon the upper edge of the casing 50 and is provided with a central opening therethrough in line with the central opening in the boss 54, so that the shaft 55, extends upwardly through the central opening in the 55 base of the cup-shaped portion 51. The sleeve 56 is provided with a collar 57, at the lower end thereof, which rests on the base of the cup-shaped casing 50, and is secured to the casing 50 by means of the pins 50'. A sleeve 58 is rotatably mounted upon

the sleeve 56, the lower edge of said sleeve abutting the upper edge of the collar 57, and the upper edge of said sleeve 58, which is inclined to a plane perpendicular to the shaft, lying so that the upper edge of said sleeve 58 forms an inclined plane. An interrupter plate, 61 is provided, having a sleeve 59 extending downwardly through the central opening in the base of the casing 51, said sleeve being provided with an inclined lower edge 60, which bears upon and co-acts with the upper edge of the sleeve 58. The interrupter lever 32 is pivotally mounted on the plate 61 and carries one of the contacts 34, the other contact 34 being carried by a bracket fixed to the plate 61 in the usual manner. A spring 62 is provided which abuts at one end against the post 63, carried by the interrupter plate 61, and normally tends to throw said interrupter lever so as to hold said contacts in engagement with each other. The rotating cam 33 is attached to the upper end of the rotating shaft 55 and is provided with a plurality of ridges 66, which extend at an angle to the axis of 90 the shaft, as clearly shown in Figure III, all of said ridges being parallel to each other. A block 64, of fibre or other suitable insulating material, is carried by the interrupter lever and is provided with a projecting portion 65, disposed at an angle to the sides of the block, as shown in Figure VI, so that, when said block 64 is held in place in the interrupter lever, the projecting part 65 extends parallel to the direction of the ridges 66. A distributor head 42 is fixed on the upper end of the shaft 55, or rather, on the upper end of the cam 33.

In the lower casing 50 there is provided the solenoid 48, which is wound on a channel-shaped frame 67, the latter being supported by brackets 68 from the base of the upper cup-shaped casing 51. The solenoid 48 is so positioned that its axis is inclined at an angle to the shaft 55. Vanes 70, which act as an armature for the solenoid, are secured to the lower sleeve 58 by means of the screws 69. These vanes 70 lie in a plane which is so inclined to the shaft 55 and to the solenoid 48, that, when the vanes are in their normal position, the end of one of them will be near one edge of the solenoid while the end of the opposite vane will be near the opposite edge of the solenoid, as is clearly shown in Figure III. The shaft and sleeve are preferably made of aluminum, or some other non-magnetic material, while these vanes are preferably made of soft iron and constitute the armature for the solenoid, that the same will offer the path of highest magnetic conductivity within the area of the solenoid. The solenoid is connected in circuit with the brushes 12 and 19, through the binding posts 71.

In Figure VII, I have shown a modifica-

tion of my invention, in which the sleeve 73 is fixed relative to the casing 50 and provided with an inclined groove 74. The interrupter plate 61 is provided with a depending sleeve 75, provided with the projection 75', which is disposed in the groove 74. The vanes 70 are secured to the lower end of the sleeve 75 by the screws 69 in the same manner that they are secured to sleeve 58 in the form of my device shown in Figures II to V, and are disposed relative to the solenoid 48 in the same manner, so that they act as an armature for the solenoids for the armature and so that the field of force generated in the solenoid by the current passing between the brushes 19 and 12 will act upon said vanes to cause the sleeve 75 to rotate with the result that the interrupter plate 61 is lifted. In this form the ridges 66 on the cam 33 are parallel to the axis of the shaft.

In Figure VIII, I have shown another modification of my device which is the same as that shown in Figure VII, except that a spring 76 is provided, which is attached at one end to the bracket 68 for supporting the solenoid, and at the other end to the sleeve 75 by means of the screw 69, so that said spring tends to assist gravity to restore the parts to their normal position and the solenoid acts against the tension of said spring in rotating the sleeve to lift the interrupter plate.

In Figures IX, X and XI, I have shown another modification of my device. In this form, the interrupter plate 61 is provided with the depending sleeve 59, provided with the arm 78 projecting laterally therefrom, and having a head 79, which is wedge-shaped, and which is disposed between the poles 83 and 82 of the solenoid 48, said poles having the opposite inclined faces 84, as is clearly shown in Figure XI. The solenoid 48 is connected in the circuit with the brushes 12 and 19 by the binding post 81. It will be seen that as the solenoid 48 is energized, pole pieces 82 and 83 will be magnetized and the head 79 will be drawn into engagement with the inclined faces 84 of the pole pieces, such action tending to rotate the sleeve 59, the lower edge of which engages the upper edge of the lower sleeve, which is inclined and acts as an inclined plane, so that the rotation of said sleeve will lift the interrupter plate 61.

From the description of the parts given above, the operation of this system should be very readily understood. The circuit, which includes the operating solenoid 48, has its terminals connected to two brushes of the machine, in this case 12 and 19, between which the voltage increases with the speed of rotation of the armature. It will be evident from a consideration of the well known theory of third brush regulation, that the

voltage between the brushes 12 and 19 increases with the speed. On rotation of the generator, in the direction indicated by the arrow in Figure I, there will be a distortion of the field, which varies with the speed, 70 this distortion being due to the cross flux of the armature, which will tend to shift the field toward that side of the field pole from which the armature rotates. This will cause an increase in the voltage drop between the brushes 12 and 19, and a decrease between brushes 11 and 19, while the main brush voltage or the voltage between the brushes 11 and 12 will remain constant.

Inasmuch as these brushes 11 and 19 form 80 terminals for the shunt field, it is evident that, as the speed increases, the current passing through the shunt field decreases, and, in consequence, the current output of the machine is held within definite limits 85 for wide speed variations. The current developed by the E. M. F. between brushes 12 and 19 will pass through the solenoid 48 and when a sufficient magnetic flux is present, 90 the vanes 70 which serve as an armature, for the solenoid, will tend to align themselves with the flux through the solenoid, and will rotate until this force exerted by the magnetic field is equal to the force exerted by the weight of the interrupter plate 95 and the parts carried thereby. The rotation of the vanes 70 will rotate the sleeve 58 and will force the interrupter plate upwardly by the cam action of the adjoining edges of the sleeves 58 and 59, to the position shown in 100 Figure IV of the drawing. The rotating cam 33 is provided with projecting ridges, which extend angularly in relation to the shaft, and, since the interrupter plate which carries the interrupter lever and the contact 105 co-operating therewith, moves axially only, it will be evident that, as the interrupter plate is raised, causing the fibre block on the interrupter lever to contact with the cam at a point higher up on the cam, the spark will 110 be advanced since the make and break in the circuit, due to the engagement and actuation of the interrupter lever by the ridges on the cam will come earlier. It is evident, therefore, that as the engine speed increases 115 and the amperage in the actuating solenoid becomes higher, the greater will be the variation in the sparking time, as the spark will be advanced more and more as the flux in the solenoid becomes greater, due to the increase in current strength. The direction of 120 rotation of the shaft is such that the spark is advanced as the speed is increased. The weight of the parts returns them to normal position so that the spark is retarded when 125 the speed decreases again.

Inasmuch as the force of magnetic attraction varies inversely as the square of the distance, the force of attraction, which the solenoid 48 exerts upon the vanes carried 130

4
by the lower end of the sleeve 58, tending to turn the sleeve and thus lift the interrupter plate, will be comparatively greater at higher speeds, as the distance to position 5 of maximum displacement is then shorter. This is desirable since the inductive reactance of the ignition circuit is great at high speeds, thus cutting down the ignition current and my arrangement compensates for 10 this factor.

In the construction shown in Figure VII, there is shown a different method of actuating the sleeve on the lower end of the interrupter plate, in which the lifting and turning movement of the interrupter plate is caused by the engagement of the tongue 75' in the groove 74. The form shown in 15 Figure VIII is identical with that shown in Figure VII, except that a spring 76 is 20 provided for restoring the parts to normal position, whereas in the other forms, I rely upon the weight of the parts to return them to the normal or lower position.

In the forms shown in Figure IX, X and 25 XI, I have devised a slightly different method of operation in which the sleeve is rotated by the arm 78 having a head 79 at the end thereof, which is drawn into engagement with the field poles 82 and 83 of 30 the solenoid 48 when the solenoid is energized, due to the passing of the current therethrough. In this embodiment of my invention, the electromagnet has the solenoid 48, the terminals 81 and the poles 82 35 and 83, and the latter are so formed that a wedge-shaped recess having faces 84 is formed, possessing an angularity greater than that of the wedge-shaped head 79 on the end of the arm 78. This wedge is normally, 40 partially advanced into the recess, and will be forced inwardly so as to include a greater flow of magnetism and thereby operate to advance the spark. By increasing the angularity of the wedge over that of the 45 recess, the acceleration of force tending to swing the arm inwardly will be somewhat diminished without decreasing materially the force of the motion.

I am aware that the particular embodiment 50 of my invention, which I have here shown and described, is susceptible of considerable variation without departing from the spirit of my invention. I have found, however, that this particular embodiment 55 is desirable from many standpoints, and, therefore, I desire to claim the same specifically as well as broadly as indicated by the appended claims.

Having thus described my invention, what 60 I claim as new and desire to secure by Letters Patent is:

1. In a system of the class described, the combination of a speed generator having a field winding and adapted to be driven by a 65 variable speed internal combustion engine,

a load circuit for said generator, an engine timer for said engine, and electromagnetic spark advance mechanism for said timer, series connections between said generator field and mechanism, and a circuit connection between the generator and the connecting ends of said field and mechanism. 70

2. In a system of the class described, the combination of a generator adapted to be driven by a variable speed internal combustion engine, a load circuit connected thereto, an ignition timer for said engine, an electro-magnet for advancing the time of operation of said timer, said generator having a pair of brushes across which the potential increases with an increase in speed, and circuit connections between said pair of brushes and said electro-magnet. 75

3. In a system of the class described, the combination of a generator adapted to be driven by an internal combustion engine, an adjustable ignition timer for said engine, means normally holding said timer in a position of retarded spark, an electro-magnet for advancing the time of said spark and circuit connections between said generator and said electro-magnet whereby as the potential of said generator increases with an increase in speed the time of operation of said timer is automatically advanced. 80

4. In a system of the class described, the combination of a generator adapted to be driven by a variable speed internal combustion engine and having a pair of main brushes, a third brush and a shunt field winding connected between said third brush and one of said main brushes, a storage battery connected to be charged by said generator, a load circuit connected to be supplied by said generator or by said battery, an adjustable ignition timer and distributor for said engine, electro-magnetic means for adjusting said timer and distributor to advance the ignition spark in said engine and circuit connections from said electro-magnetic means to said third brush and said other main brush. 100

5. In a system of the class described in combination, a generator having two main brushes between which the voltage remains substantially constant; and a third brush displaced from said main brushes; and an electro-magnetic spark advancing device connected to said third brush and one of said main brushes, between which brushes the voltage increases approximately as the speed. 115

6. An automatic spark controlling mechanism comprising the combination of a generator; main brushes associated with said generator; a third brush, between which and said main brushes the voltage varies with generator speed of revolution; ignition time controlling mechanism; and a circuit including said third brush and one main 120

- brush, adapted to actuate the ignition time controlling mechanism upon variation of voltage between said last named brushes.
7. In a battery charging and ignition system, the combination of a generator; having a pair of load brushes and a third brush displaced from one of said load brushes, between which brushes the voltage increases with the speed; spark timing mechanism; a circuit connected to said third brush and said one load brush, including a solenoid; a rotatable core; and vanes associated with the core, said core being adapted, on the variation of energy in the solenoid, to actuate the spark timing mechanism.
8. An automatic spark timing mechanism comprising the combination of a generator; having means for regulating the current output as the speed varies, including a current regulating field winding, said generator being provided with three brushes, between two of which brushes the voltage decreases with the speed and the shunt field is connected, and between the third brush and one of said two brushes, the voltage increases with the speed; a circuit connecting said last two brushes; and spark control mechanism operatively connected in said circuit.
9. In a battery charging and ignition system, the combination of a generator, having two main brushes and a third brush; current regulating means connected with the third brush and one of said main brushes; an ignition system connected with said main brushes; and means, comprising a solenoid and movable core, connected to said third brush and the other main brush and adapted when the solenoid is energized to advance the time of ignition in accordance with the increase in engine speed.
10. In a battery charging and ignition system, the combination of a generator, having a pair of main brushes and a third brush; an ignition circuit comprising a primary circuit connected across said main brushes; ignition timing mechanism; a circuit connected from said third brush to one of said main brushes; and an automatic spark advancing mechanism controlled by the current in said circuit.
11. In a battery charging and ignition system, the combination of a generator; a pair of main brushes; a third brush; an ignition circuit connected across said main brushes and comprising timing and distributor mechanism; a circuit connected from said third brush to one of said main brushes, so that the voltage in said circuit increases as the speed of the generator increases; and spark advancing means connected in said circuit and actuated thereby.
12. In a battery charging and ignition system, the combination of a generator; a pair of main brushes; a third brush; an ignition circuit connected across said main brushes and comprising distributing and timing mechanism; a circuit connected from said third brush to one of said main brushes; a solenoid connected in said circuit; and spark advancing mechanism actuated by said solenoid.
13. In a battery charging and ignition system, the combination of a generator; a pair of main brushes; a third brush; an ignition circuit connected across said main brushes, and comprising distributing and timing mechanism; a circuit connected from one of said main brushes to said third brush, said circuit being so connected that the voltage between the terminals thereof increases as the generator speed increases; a solenoid connected in said circuit; and spark advancing mechanism actuated by said solenoid.
14. In a battery charging and ignition system, the combination of a generator; a pair of main brushes; an ignition circuit connected across said main brushes, and comprising distributing and timing mechanism; a third brush; a circuit, including a shunt winding, connected from said third brush to one of said main brushes, said circuit being so connected that the field intensity decreases as the generator speed increases; means for automatically advancing said distributing and timing mechanism; and a circuit connecting said means with said third brush and said other main brush.

In testimony whereof I affix my signature.

HENRY R. DAVIES.
